CLAIM

The ornamental design for a container, cap and carabiner set as shown and described.

DESCRIPTION

FIG. 1 is a perspective view of the container, cap and carabiner set of the present invention;

FIG. 2 is a front elevational view of the invention shown in FIG. 1;

FIG. 3 is a rear elevational view of the invention shown in FIG. 1;

FIG. 4 is a left side elevational view of the invention shown in FIG. 1;

FIG. 5 is a right side elevational view of the invention shown in FIG. 1;

FIG. 6 is a top view of the invention shown in FIG. 1;

FIG. 7 is a bottom view of the invention shown in FIG. 1;

FIG. 8 is a perspective view of the container shown in FIG. 1 without the cap;

FIG. 9 is a front elevational view of the container shown in FIG. 8;

FIG. 10 is a rear elevational view of the container shown in FIG. 8;

FIG. 11 is a left side view of the container shown in FIG. 8;

FIG. 12 is a right side view of the container shown in FIG. 8;

FIG. 13 is a top view of the container shown in FIG. 8;

FIG. 14 is a bottom view of the container shown in FIG. 8;

FIG. 15 is a perspective view of the cap shown in FIG. 1 without the container;

FIG. 16 is a front elevational view of the cap shown in FIG. 15;

FIG. 17 is a rear elevational view of the cap shown in FIG. 15;

FIG. 18 is a left side elevational view of the cap shown in FIG. 15;

(Continued)

FIG. 19 is a right side elevational view of the cap shown in FIG. 15;
 FIG. 20 is a bottom view of the cap shown in FIG. 15;
 FIG. 21 is a top view of the cap shown in FIG. 15;
 FIG. 22 is a perspective view of a carabiner of the cap shown in FIG. 15;
 FIG. 23 is left side view of the carabiner shown in FIG. 22;
 FIG. 24 is a right side view of the carabiner shown in FIG. 22;
 FIG. 25 is a front elevational view of the carabiner shown in FIG. 22;
 FIG. 26 is a rear elevational view of the carabiner shown in FIG. 22;
 FIG. 27 is a top view of the carabiner shown in FIG. 22; and,
 FIG. 28 is a bottom view of the carabiner shown in FIG. 22.
 The drawings illustrate a container, cap and carabiner set.
 The container is shown in FIGS. 1 through 14 and illustrates
 a plurality of substantially wave-like grooves and protrusions
 thereon. Contour lines are included in the various
 views of FIGS. 1 through 28 to depict surface curvature,
 flatness and/or other shapes. Illustrative portions that are
 depicted in broken lines form no part of the claimed design.
